UNITED STATES PATENT OFFICE.

ARTHUR J. HURD, OF WAUSAU, WISCONSIN.

GARDENER'S STOOL.

1,383,542.

Specification of Letters Patent. Patented July 5, 1921.

Application filed September 7, 1920. Serial No. 408,616.

To all whom it may concern:

Be it known that I, ARTHUR J. HURD, a citizen of the United States, residing at Wausau, in the county of Marathon and State of Wisconsin, have invented a new and useful Gardener's Stool, of which the following is a specification.

This invention relates to agricultural implements and more particularly to a gardener's stool and has for its object the provision of a portable seat, whereby a person may be relieved of the strain incident to the position necessarily assumed while weeding and thinning vegetable crops.

15 A further object is the provision of a comfortable seat which is readily moved and remains steady when in use.

Still further it is an object of the invention to provide adjustable means whereby the seat may be elevated to suit the requirements of an operator or for hillside work, adjustable means also being provided for the accommodation of rows of different widths.

25 With these and other objects in view which will appear as the description proceeds the invention resides in the novel combination and arrangement of parts herein-after described and particularly pointed out in the appended claims, it being understood that minor changes may be made in the device without departing from the spirit of the invention or sacrificing any of the advantages thereof.

30 In the drawing:—

Figure 1 is a view in side elevation;

Fig. 2 is a bottom plan view;

Fig. 3 is a transverse section taken on line 3—3 of Fig. 2; and

40 Fig. 4 is a detail view of a portion of the structure.

Referring to the drawing by characters of reference the numeral 1 designates a platform or seat, having secured to the under-side thereof cleats 2. Channel irons 3 on which the cleats 2 rest, have their flanges downturned for the reception of supporting members 4. The members 4 are of channel iron cross section, each member comprising a transversely extended portion 5 and a vertical portion 6. Elongated slots 7 and 8 are formed in the portions 5 and 6 respectively.

50 A member 4 is provided for each of the corners of the seat 1 and is held in place by a bolt 9 which passes through the seat 1, cleat 2, channel 3 and slot 7 in the member 4.

To the vertical portions 6 at one end of the device are secured legs 10 made of channel iron and provided at the lower end with a foot 11, the same being attached to the leg portion in any approved manner and having upturned ends to permit free and easy movement over the soil. A bolt 12 passes through the leg 10 and the slot 8 adjustably securing the leg to the member 4.

60 The portions 6 at the other end of the seat have secured thereto by means of bolts 13, legs 14, similar to the legs 10, each being provided with a wheel 15. A block 16 secured to the channel 14 carries a stub axle 17 on which the wheel is mounted. The wheels being provided with ball-bearings if desired.

65 A handle 18 is attached to the seat for use in moving the device along the row.

Attached to the seat is a socket 19 for the reception of the stem 20 of a canopy or sunshade 21.

In use the device is placed astride a row of plants, the operator moving it along the row as occasion requires.

70 Adjustment of the device for rows of different widths is provided for by reason of the slots 7 in the member 4, so that the legs may be extended for straddling rows of greater width or retracted to pass between the rows if necessary.

75 Adjustment of the legs through the slots 8 enables a person to raise or lower the seat to suit the individual operator, this adjustment also permitting the legs on one side of the device being lowered to maintain an approximately level seat for work on a hillside.

80 The wheels at one end permit easy movement of the device from one point to another and the shoe portions render it steady when in use.

85 Having thus described the invention what is claimed is:—

1. A gardener's stool comprising a seat; pairs of soil engaging supports disposed adjacent to the ends of the seat; and means for connecting the supports with the seat to effect a vertical adjustment between the support and the seat and to effect a horizontal adjustment between the supports of each pair.

100 2. A gardener's stool comprising a seat; pairs of soil engaging supports disposed adjacent to the ends of the seat; the supports at one end of the seat being provided with

wheels for engaging the soil, the supports at the opposite end of the seat having soil engaging shoes whereby movement of the wheels is retarded and a connecting member 5 including horizontal and vertical portions whereby the supports are connected to the seat to effect horizontal adjustment between the supports of each pair and to effect vertical adjustment between the supports and the 10 seat.

3. In a device of the class described, a seat; cleats disposed adjacent to the ends of the seat; pairs of adjustable supports carried by the cleats, each of said supports comprising a horizontal portion and a vertical portion, the horizontal portion having a longitudinal slot; a bolt passing through the slot and cleat for connecting the said support to the seat, whereby horizontal adjustment of the support is effected.

4. In a device of the class described, a seat; pairs of adjustable supports disposed adjacent to the ends of the seat, each of said supports comprising a horizontal portion

and a vertical portion, each portion being 25 of approximately U cross-sectional shape, the horizontal portion having a longitudinal slot; means for securing the horizontal portion to the seat; whereby through said slot horizontal adjustment of the support 30 is effected, the vertical portion of the support having a longitudinal slot; a leg for each of the vertical supports, a bolt passing through the leg and slot in the vertical portion for securing the leg to the support, 35 whereby vertical adjustment of the leg is effected; soil engaging shoes connected to the legs at one end of the seat and wheels connected to the legs at the other end of the seat.

In testimony that I claim the foregoing as my own, I have hereto affixed my signature in the presence of two witnesses.

ARTHUR J. HURD.
